UNITED STATES PATENT OFFICE.

RAYMOND M. KELLY, OF POTOSI, WISCONSIN.

WRENCH.

1,145,067.

Specification of Letters Patent.

Patented July 6, 1915.

Application filed November 22, 1912. Serial No. 732,911.

To all whom it may concern:

Be it known that I, RAYMOND M. KELLY, a citizen of the United States, residing at Potosi, in the county of Grant and State of 5 Wisconsin, have invented certain new and useful Improvements in Wrenches, of which the following is a specification.

My invention relates to wrenches with special references to those that are quickly adjustable and the object is to provide a wrench that is quickly adjusted to grasp nuts, pipes or bodies of varying and widely different sizes and which is easily adjusted and can be manufactured at comparatively small 10 cost.

It will be fully shown in the following specification and illustrated in the drawing, the manner of construction and mode of operation.

20 Figure 1 is a side elevation of one side of my wrench when open. Fig. 2 is a side elevation of the wrench from the opposite side of Fig. 1. Fig. 3 is a perspective view of the wrench when open. Fig. 4 is a perspective view of the movable jaw removed. Fig. 5 is a cross section of the stud that pivots the two handles together.

Like letters of references denote corresponding parts in all the figures.

30 Referring to the drawings 2 represents one of the jaws which is permanently attached to a handle 4. In the handle 4 is a slot 5 in which is pivoted a movable jaw 6 by the pivot pin 8. This movable jaw, 35 shown in Fig. 4, is recessed at 10 and provided with an opening 12 in which opening is pivoted a lever arm 14 by the pivot pin 15. To said lever arm is rigidly secured a pin 16 of V shape adapted to travel 40 in a slot 18 in the handle 4 of the jaw 2. The slot 18 is also provided with notches 22 which are adapted to be engaged by the pin 16 of the handle 14. As the pin 16 is of V shape with rounded back 45 and rigidly fixed to the lever 14, as shown in Fig. 5, it will readily engage the V-shaped notches in the slot 18 and will not slip or become disengaged when the jaws are in engagement with a nut or other article. This 50 jaw 6 is also provided with teeth 20 which preferably turn toward the outer edge of the jaw. It will be seen that when the lever 14 is raised and opens the jaw 6 that the jaw will be forced downwardly with the pivot 55 pin 8 in the slot 5 and when the lever 14 is

being closed, will force the jaw 6 toward the fixed jaw with one end of the jaw moving in the arc of a circle.

For the purpose of cutting off wire and the like there is provided in the handle 4 of the jaw 2 a rectangular notch 24 which is adapted to be engaged by the head of the lever 14 and cuts off the wire.

In the operation of the wrench the movable jaw is adjusted to the size of the nut, 65 pipe or other article to be operated upon, by moving the lever 14 up or down with the pin 16 in the slot 18, and at the same time the pivot 8 of the movable jaw will be moved up or down in the slot 5. When the adjustment 70 is complete the V shaped part of the pin 16 will be in engagement between two of the teeth 22. Then the operator as he closes the lever 14 forces the movable jaw 6 against the nut and, since one end of the jaw acts in the 75 arc of a circle it will grasp rigidly the nut and crowd it toward the throat of the jaws.

It will be seen that the adjustment can be made very quickly and since the teeth 22 in the slot 18 are near to each other, the adjustment can be made very accurately, also since the various parts can be cast, the wrench 80 can be made at small cost.

Having now described my invention what I claim is:

In a wrench of the character described, a handle having a jaw formed integrally therewith, and provided with a plurality of longitudinally disposed slots, one of said slots having a smooth inner surface and the other slot being provided with a series of notches on one of its inner surfaces, a movable jaw provided with a recess upon one side suitably pivoted in one of said slots, and a lever pivotally connected within the recess of the 90 movable jaw and provided with a pin rigidly secured thereto, said pin adapted to travel in the slot provided with the notches and engage the notches of said slot, said lever adapted to operate the movable jaw 95 with one end of the jaw traveling in the arc of a circle toward and from the fixed jaw, as and for the purpose set forth.

In testimony whereof I affix my signature in presence of two witnesses.

RAYMOND M. KELLY.
